UNITED STATES PATENT OFFICE.

CHARLES JUSTIN KENNEDY, OF DULUTH, MINNESOTA, ASSIGNOR TO NORTHERN NOVELTY MANUFACTURING COMPANY, OF DULUTH, MINNESOTA, A CORPORATION OF SOUTH DAKOTA.

DEVICE FOR CLEANING AND DRYING SAFETY-RAZOR BLADES.

1,179,359.

Specification of Letters Patent.

Patented Apr. 11, 1916.

Application filed August 30, 1915. Serial No. 48,064.

To all whom it may concern:

Be it known that I, CHARLES JUSTIN KENNEDY, a citizen of the United States, residing at 318 West Second street, in the city 5 of Duluth, county of St. Louis, and State of Minnesota, have invented a new and useful Device for Cleaning and Drying Safety-Razor Blades, and of which the following is a specification.

10 My invention consists of two thin spring-like metal plates, preferably about two inches in length, one inch in width, and one-sixty-fourth inch in thickness, and preferably bent or arched outward at a slight 15 angle from each other, so that a razor blade may be inserted between the two plates without damage to the fine edges of said blade; said plates being joined together at the center by a small screw, bolt or rivet, 20 so that the two inner faces may be exactly opposite, and meet evenly when pressed together; each plate, however, having a thin rubber pad about three-eighths of an inch in thickness, about the same width as the metal 25 plate, and about half an inch in length; said rubber pad being attached to the inner surface of one end of each plate by means of cement, glue, or a screw or rivet; and a felt pad of same size as the rubber pad 30 attached to the inner surface of each plate at the opposite end to the rubber pad, so that the two rubbers will meet together evenly, and the two felt pads will meet together evenly when the plates are pressed 35 together.

The use and object of my device are, first to clean soap, dirt, hair, or water off the razor blade after its use for shaving; and second, to dry the razor blade after cleaning same, thereby preventing rust or discoloring of the steel, and keeping the blade 40 bright and in good order, thus increasing also its time of usefulness. The cleaning is done by inserting the razor blade between the rubber pads, and pressing the latter together with the finger and thumb, thus wiping the blade; the drying is done by inserting the razor blade between the felt pads, pressing the latter together with the

finger and thumb with a wiping motion. I 50 attain these objects by the device illustrated in the accompanying drawing, in which—

Figure 1 is a perspective of the entire device, Fig. 2 a side view, and Fig. 3 represents the individual parts of the device. 55

Similar letters refer to similar parts throughout the several views.

Letters *a*, *a*, represent the metal plates, bent or arched slightly outward at points *g*, *g*; *b*, *b*, represent the two rubber pads; *c*, *c*, represent the felt pads; *d* represents the screw or rivet fastening plates together; *e*, *e*, *e*, *e*, represent screws or rivets attaching the pads to the plates; *f*, represents a thin block of metal or wood between the 60 plates at the point where they are fastened together by the screw or rivet, *d*; said block being of the same width as the metal plates, about three-eighths of an inch in thickness, 65 about a third of an inch in length and 70 preferably secured in any desired manner to one of the plates.

Fig. 2 is a side view of the device; letters *a*, *a*, representing the metal plates; *b*, *b*, the rubber pads; *c*, *c*, the felt pads; *d*, the 75 screw or rivet fastening plates together; *e*, *e*, *e*, the screws or rivets fastening pads to place; and *f*, separating block of wood or metal between the plates.

Fig. 3 represents the individual parts of 80 the device, as follows: *a*, *a*, the metal plates; *b*, *b*, the rubber pads; *c*, *c*, the felt pads; *d*, the screw or rivet fastening plates together; and *f*, the separating block between the 85 plates.

I claim, therefore, for my invention.

A device of the character described, comprising two pieces of resilient sheet metal of substantially the same size and shape 90 united at their centers, arched or bent apart at their ends, and having attached to the opposed faces of their adjacent ends blade engaging pads, substantially as and for the purpose described.

CHARLES JUSTIN KENNEDY.
